GEORGES GALLAY, OF LE SENTIER, SWITZERLAND

METHOD AND MEANS FOR FINISHING TIMEPIECE BALANCE WHEELS

Application filed May 25, 1931, Serial No. 539,890, and in Switzerland August 12, 1930.

This invention relates to a method and means for finishing timepiece balance wheels and has as its primary object to provide balance wheels having rigorously circular rims which are strictly concentric to the axis of the wheel.

It is also an object of the invention to provide means for accurately finishing the inner surface of the rim of the balance wheel.

10 In the drawing, which represents a suitable embodiment of an apparatus for carrying the invention into effect,

Figure 1 is a plan view of the apparatus; Figure 2 is an elevation;

15 Figure 3 is an end view of a part of the apparatus with the balance wheel to be finished secured thereto.

The shaft 1 can be rotated by any appropriate means about its longitudinal axis and 20 carries at its end and centered relative to its axis, a balance wheel A which is to be finished. A tool carrier 2 is disposed opposite the shaft 1 and can slide in a longitudinal guide 3 provided on the frame 11 of the machine. This tool carrier is adapted to receive a cutter 4 and also supports a transverse arm 5 provided with a cam 6. The opposite end of the tool carrier supports a transverse arm 7 to each end of which there 25 is fixed a pin 12. Similar pins 9 are fixed to the guide 3 and springs 8 connecting each pair of pins 8 and 12 constantly urge the arm 7 and the tool carrier 2 towards the shaft 1.

30 The end face of the shaft 1 carries diametrically opposite each other two fingers 10. The balance wheel A is disposed in such a way on the end face of the shaft 1 that the longitudinal axis of its arm B coincides with the 40 connecting line of the centers of the two fingers 10.

The balance wheel which is already cut out, is attached to the shaft 1 and the cutter 4 is disposed so that its cutting edge engages the 45 inner surface E of the balance wheel rim. The cutting movement is then produced by rotation of the shaft 1, while the feed motion may be given the tool carrier 2 by any known means. At each half turn of the shaft 1 one 50 of the fingers 10 acts on the cam 6 and pushes

the tool carrier backwards against the action of the springs 8 for an amount which is equal to the thickness of the arm B of the balance wheel; this arm does therefore not prevent the movement of rotation of the shaft 1, the cutter being pushed back while the arm passes in front of it.

55 By means of the described apparatus one obtains balance wheels which are finished on the inner surface of their rim, this latter being therefore of strictly circular diameter and absolutely concentric to its axis.

60 The machine could also be constructed that the shaft moves longitudinally in order to let the arm of the balance pass the cutter or that the shaft and the tool carrier both move in opposite directions. The movement of the carrier relative to the shaft could be obtained also by means of gears or by an appropriate system of levers.

70 I claim:

1. The method of finishing the inner surface of the rims of wheels having arms or 75 spokes, which consists in centering the wheel on a rotatable work carrier, rotating the work carrier with the wheel thereon, feeding a tool radially against the inner surface of the rim of the wheel, and axially shifting the tool away from, and towards the work carrier in timed relation to the rotation thereof to provide for the passage of the spokes of the wheel 80 in front of the tool.

2. The method of finishing the inner surface of rims of wheels having arms or spokes, which consists in centering the wheel on a 85 rotatable work carrier, rotating the work carrier with the wheel thereon, feeding a cutting tool radially against the inner surface of the rim of the wheel, and effecting relative axial movement between the work carrier and the tool in timed relation to the rotation of the work carrier to provide for the passage of the spokes in front of the tool.

90 3. The method of finishing timepiece balance wheels having a punched out rim and arms, which consists in centering the wheel on a work carrier, feeding a cutting tool radially against the inner surface of the rim of the wheel, effecting relative rotative movement 95 between the tool and the work carrier, and 100

effecting relative axial movement between the tool and the work carrier in timed relation to the movement of rotation to provide for the passage of the balance wheel arms in front of the tool.

- 5   4. A lathe for finishing the inner surface of the rim of wheels having arms or spokes, comprising a rotatable work carrier adapted to have the wheel centered on a face thereof, fingers projecting from said face and corresponding in number to the number of spokes of the wheel to be finished, said fingers being situated exteriorly of the wheel rim when centered on this face and on the longitudinal axis of each spoke thereof, a tool disposed to work on the inner face of the wheel rim, a tool carrier, spring means acting to approach the tool carrier to the work carrier, and abutting means on the tool carrier situated in a predetermined position relative to the tool and coacting with said fingers on the work carrier for effecting relative axial movement between the tool carrier each time a spoke of the wheel approaches the tool.
- 10   25   In testimony whereof I affix my signature.
GEORGES GALLAY.
